UNITED STATES PATENT OFFICE.

DEAN SOUTHWORTH, OF BRAINTREE, MASSACHUSETTS.

DESIGN FOR A SPOON.

SPECIFICATION forming part of Design No. 21,463, dated April 12, 1892.

Application filed March 8, 1892. Serial No. 424,232. Term of patent 3½ years.

To all whom it may concern:

Be it known that I, DEAN SOUTHWORTH, a citizen of the United States, residing at Braintree, in the county of Norfolk and State of Massachusetts, have invented and produced a new and original Design for Spoons, of which the following is a specification.

This design has for its object to provide a novel handle for spoons and other table-ware, which presents a handsome and characteristic appearance to the eye.

The leading feature of the design resides in a handle having thereupon the representation of a man wearing a hat thrown back on the head and a pair of boots strung or suspended across the shoulders.

The design is illustrated by the accompanying drawing, in which the figure is a broken perspective view of a spoon embodying my design.

In the drawing, the numeral 1 indicates the handle of a spoon or other article of table-ware having thereupon the representation of a man wearing a hat which is thrown back on the head. The boots 2 are represented as suspended from the shoulders by strings 3.

The design provides a novel and handsome spoon-handle, which presents a characteristic appearance to the eye.

What I claim is--

The design for a spoon or similar handle, substantially as shown and described.

In testimony whereof I have hereunto set my hand and affixed my seal in presence of two subscribing witnesses.

DEAN SOUTHWORTH. [L. S.]

Witnesses:

EWELL A. DICK,
JAMES A. RUTHERFORD.
